UNITED STATES PATENT OFFICE.

GEORGE W. SOULÉ, OF MERIDIAN, MISSISSIPPI.

CLAMP.

SPECIFICATION forming part of Letters Patent No. 752,424, dated February 16, 1904.

Application filed July 27, 1903. Serial No. 167,237. (No model.)

To all whom it may concern:

Be it known that I, GEORGE W. SOULÉ, a citizen of the United States, residing at Meridian, in the county of Lauderdale and State of Mississippi, have invented a new and useful Improvement in Clamps, of which the following is a specification, reference being had to the accompanying drawings.

My invention relates particularly to that class of clamps which are used by foundrymen for securing together the sections of flasks.

The invention may also be used by carpenters and others.

The object of the invention is to produce a clamp which is conveniently adjustable so as to vary the distance between the jaws and which can be cheaply manufactured and readily applied for use. For foundrymen's use the clamp consists of only two pieces, and these pieces may be duplicates of each other, and said pieces may be ordinary castings, and they need no machine-work or other finishing unless it be cleaning in a tumbler.

In the accompanying drawings, Figure 1 is a view of the two members of my improved clamp, the dotted lines showing how these parts are to fit to each other. Fig. 2 is a back view of the clamp composed of the parts shown in Fig. 1. Fig. 3 is a side view of the same clamp. Fig. 4 is a front or inside view of the same clamp. Fig. 5 is a section on the line 5-5 of Fig. 2 looking toward the right. Fig. 6 is a detail view showing a binding-screw applied to one of the jaws of the clamp. Fig. 7 is a perspective of my improved clamp. Fig. 8 is a perspective view of the clamp applied.

Referring to said drawings, 11 are the members which constitute the clamp. At one end of each member is a jaw 2, extending laterally at approximately right angles to the body 3. At the other end of each member there is an arm 4 extending rearward and then laterally with reference to the plane in which the body 3 and said jaw lie. The two members are applied to each other with their sides partially overlapping and with their front faces lying in the same plane, the arm 4 of one member extending across and engaging the back of the other member. This makes it necessary that the lateral portion of the arm 4 be located

rearward a proper distance to bring its front face rearward approximately the same distance as the back of its member. The front face of said arm preferably conforms in reverse approximately to the transverse profile of said back. The back of each member is preferably provided with an oblique or beveled face extending from near the meeting plane of said members outward and forward and the arm 4 directed forward and outward correspondingly. This permits the arm 4 to extend forward and partially embrace the body of the adjacent member and restrain lateral movement of said member. The back of each member is provided with a series of notches 5, adapted to receive the arms 4. Said notches are preferably equally spaced, so that each of said arms 4 may at the same time rest in a notch. When said arms so rest in any of said notches, the two members are held against longitudinal movement upon each other, and the clamp may then be applied to the flask and secured in the usual way by wedges. By placing said arms into different notches the length of the clamp may be varied. Said notches 5 are preferably formed obliquely, so as to constitute ratchets, the part of each notch toward the arm 4 presenting a transverse face 6, adapted to abut against the face of the arm 4, which is directed toward the jaw of its member. Thus there is no resistance to the movement of the members over each other in the proper direction to cause the jaws to approach each other. Obviously arm-engaging means other than said notches may be used.

It will be observed that, as shown in the drawings, the members 11 are duplicates. This makes it possible to make a complete clamp or any number of complete clamps by casting from a single pattern. This fact that the members are duplicates is, furthermore, a material advantage in using the clamp, for any two members that are taken up by the workman will form a clamp.

It will be observed that no auxiliary devices or attachments are required for joining the two members to each other. No bolts, screws, springs, or keys are required; yet the engagement between the two members is entirely effective and adequate for all uses.

If so desired, two members which are duplicates excepting as to length may be combined to form a clamp. Practice has shown that it is a convenience to have approximately equal numbers of members of two different lengths. Then from the stock of members the workman can readily assemble clamps of three different average lengths—first, by combining two short members; second, by combining a short and a long member, and, third, by combining two long members. In ordinary foundry practice clamps ranging from eight inches to twenty-four inches are needed, and they usually differ only one inch in length. Hence when they are non-adjustable a large number of the clamps must be kept in stock.

For carpenters' and joiners' use and for similar purposes it may be desirable to use a screw for completing the engagement after the clamp has been set as closely as may be by use of the notches on the members. Fig. 6 shows a screw 7 extending through one of the jaws 2. Said screw may be driven forward to bear against the object to which the clamp is applied.

I claim as my invention—

1. A clamp consisting of two overlapping members each having a forward-extending jaw at one end and at its other end an arm extending across and forward of the rearmost portion of the back of the other of said members, and suitably-spaced arm-engaging means on one of said members of less engaging depth than the forward extension of the arm, substantially as described.

2. A clamp consisting of two overlapping members each having a forward-extending jaw at one end and at its other end an arm extending across and forward of the rearmost portion of the back of the other of said members, and suitably-spaced arm-engaging means on each of said members of less engaging depth than the forward extension of the arm, substantially as described.

3. A clamp consisting of two overlapping members each having a forward-extending jaw at one end and at its other end an arm extending across and forward of the rearmost portion of the back of the other of said members, and suitably-spaced arm-engaging notches on the back of one of said members of less engaging depth than the forward extension of the arm, substantially as described.

4. A clamp consisting of two overlapping

members each having a forward-extending jaw at one end and at its other end an arm extending across and forward of the rearmost portion of the back of the other of said members, and suitably-spaced arm-engaging notches on the backs of said members of less engaging depth than the forward extension of the arm, substantially as described.

5. A clamp consisting of two overlapping members each having an oblique or beveled back, one of said backs having suitably-spaced arm-engaging means, and each of said members having a forward-extending jaw at one end and at its other end an arm extending across and conforming approximately to the back of the other of said members, substantially as described.

6. A clamp consisting of two overlapping members each having an oblique or beveled back, one of said backs having suitably-spaced notches, and each of said members having a forward-extending jaw at one end and at its other end an arm extending across and conforming approximately to the back of the other of said members, substantially as described.

7. A clamp consisting of two overlapping members each having a forwardly-extending jaw at one end and at its other end an arm extending across and forward of the rearmost portion of the back of the other of said members, and suitably-spaced ratchet-teeth on one of said members, substantially as described.

8. A clamp consisting of two overlapping members each having a forwardly-extending jaw at one end and at its other end an arm extending across and forward of the rearmost portion of the back of the other of said members, and suitably-spaced ratchet-teeth on each of said members, substantially as described.

9. A clamp consisting of two overlapping members each having an oblique or beveled back, one of said backs having ratchet-teeth, and each of said members having a forwardly-extending jaw at one end and at its other end an arm extending across and conforming approximately to the back of the other of said members, substantially as described.

In testimony whereof I have signed my name, in presence of two witnesses, this 17th day of July, 1903.

GEORGE W. SOULÉ.
